UNITED STATES PATENT OFFICE

WILHELM SCHÖTTELDRÉIER, OF NACHRODT IN WESTFALEN, GERMANY, ASSIGNOR TO
VEREINIGTE STAHLWERKE A. G. DÜSSELDORF, A FIRM

METHOD OF HEATING ROLLS

Application filed August 5, 1927, Serial No. 210,884, and in Germany August 7, 1926.

In the production of thin fine sheets of metal it is necessary first of all to preheat the rolls to a definite temperature before large and thin sheets can be rolled. It has hitherto been the practice first to roll thick sheets, the rolls being heated and gradually reaching a temperature that makes it possible for large and thin sheets to be rolled. It takes a fairly long time to reach the rolling temperature which is necessary for rolling out the large and thin sheets. Furthermore, the rolls are frequently broken by reason of the stresses that arise under the application of sudden and localized heating. Moreover, this method of heating very readily damages the surface of the ground rolls.

It has been proposed to heat the rolls by electric resistance heating. The devices for the purpose are, however, so complicated and expensive, while at the same time the process is so uneconomical that hitherto they have not been put to general practical use.

The invention avoids the disadvantages connected with the known methods referred to.

According to the invention rolls can be pre-heated to the necessary temperature in a very short space of time, and with the minimum expenditure of energy. In this connection it is important for heating to proceed from inside outwardly so that the whole roll shall be completely heated, the effect being that large and thin sheets can thereupon be rolled. In addition, the cost of the rolls is reduced and the capacity of the rolling mill for producing large thin sheets is increased.

According to the invention the rolls are heated by magnetic hysteresis and eddying currents. This is possible if the poles of alternating current magnets are brought close to the rolls so that the rolls are disposed between the poles of the magnets.

The invention is illustrated in the accompanying drawings in its application to an ordinary sheet metal rolling mill.

Fig. 1 is a section through the rolling mill on the line I—I of Fig. 2 and Fig. 2 is a plan view of the rolling mill.

In the drawings the rolls *a* are disposed between the poles of two movable alternating

current magnets, the cores of the magnets (which are provided with windings *e*) being divided into separate sheet-metal bundles *b* in order better to carry off the heat transmitted from the rolls.

The distance apart of the bundles *b* is determined by bronze bushes *c*. The separate bundles are held together by bronze pins or bolts *g*. The current induced by the alternating current winding produces eddying currents and magnetic hysteresis in the rolls, which together ensure rapid heating. The loss of the heat produced may be reduced to a minimum by a sheetmetal jacket lined with asbestos.

The rolls having been sufficiently heated, which operation takes but a short time, the pair of magnets is removed and the rolling of large thin sheets can thereupon commence.

If no alternating current is available, but only direct current, the same procedure as described may be followed, except that the rolls must be rotated if equal results are to be secured, the period of heating being dependent upon the speed of rotation and the strength of field of the magnets. In this way the process can be adapted to all working conditions.

What I claim and desire to secure by Letters Patent of the United States is:

1. An apparatus for pre-heating the rolls of a sheet rolling mill, comprising U-shaped electro-magnets extending on opposites of said rolls, having the opposite poles of the same magnet adjacent different rolls so that on opposite sides of each roll is a pole of different character in a different magnet.

2. An apparatus for pre-heating the rolls of a sheet rolling mill, comprising U-shaped electro-magnets extending on opposites of said rolls, having the opposite poles of the same magnet adjacent different rolls so that on opposite sides of each roll is a pole of different character in a different magnet and means for removing said magnets from the vicinity of the rolls.

3. An apparatus for pre-heating the rolls of a sheet rolling mill, comprising U-shaped electro-magnets extending on opposites of

said rolls, having the opposite poles of the same magnet adjacent different rolls so that on opposite sides of each roll is a pole of different character in a different magnet, said magnets having sectional cores comprising sections held in spaced relation by means of spacers and bolts.
